ELECTRIC SIGNALING APPARATUS AND CIRCUITS.

1,132,267.

Specification of Letters Patent.

Patented Mar. 16, 1915.

Original application filed August 15, 1890, Serial No. 361,048. Divided and this application filed February 10, 1902. Serial No. 93,285 $\frac{1}{2}$.

To all whom it may concern:

Be it known that I, FELIX BENEDICT HERZOG, Ph. D., a citizen of the United States, and a resident of the city, county, and State of New York, have invented a new and useful Improvement in Electric Signaling Apparatus and Circuits, of which the following is a specification.

This is a division or continuation of a pending case S. N. 361,048 filed on Aug. 15, 1890, since patented on Feb. 11, 1902 as 693,014, and is to be considered as related to two other applications S. No. 93,284 $\frac{1}{2}$ and S. No. 93,286 $\frac{1}{2}$ filed on even date herewith as co-divisions of the same original case.

The improvements herein set forth are of general utility in the arts, although they have special reference to a system of communicating or signaling in which one or a plurality of transmitters more or less automatically operated are connected with a receiving apparatus at one or more distant stations.

This invention relates more particularly to the transmitter of a signaling apparatus, and has for its object the facilitating of the operation of such transmitters, the increasing of the capacity thereof so as to send more than one signal to make a permanent record of the signals transmitted, and to also identify and leave a record at the transmitting station of the operator who signals from that station.

Referring to the drawings, Figure 1 is a front view of one embodiment of the invention, Fig. 2 is a front view of another embodiment, showing also novel arrangement of circuits which have utility with other transmitters; Fig. 3 a detail of the form shown in Fig. 1; Fig. 4 a detail of the form shown in Fig. 2; Fig. 5 is another embodiment and Fig. 6 is still another embodiment; Figs. 7, 8 and 9 are details. Fig. 10 is a diagrammatic side elevation illustrating a receiving instrument which may be used with my transmitters.

Referring more particularly to the drawings, the form of transmitter shown in Fig. 1 comprises the usual break wheel A with a spring brush N bearing thereon, and adapted thereby to break up a continuous current into a series of impulses, which being transmitted to line acts to operate a receiving instrument at a distant station in any suit-

able manner. This type of break wheel is 55 fully described in several of my previous patents; for instance #289,834, 315,783, 560,212 and 628,464, and need not be more particularly described than to say that it is driven by any suitable motor, such as spring 60 3 shown, and carries a large disk A^x on which are mounted a plurality of push-buttons D, as shown. The ratchet R is also fixed to the break wheel A, the periphery of which is shown through the broken-away 65 portion of the disk A^x, and this ratchet is adapted to drive through spring-pressed pawl 12 a large pinion 12^a of a clock train. This clock train may be of any suitable construction as shown in several of my previous 70 patents referred to, in which the gear 12^a meshes with small gear 12^b, of escape wheel 12^c. The speed of the escape wheel is controlled by oscillating verge or escapement pawl 6, carrying weighted pendulum arm 75 6^a. In setting the device shown in Fig. 1 ready for operation, the disk A^x and break wheel A are turned clockwise to wind up the spring 3, attached at its outer end to the frame of the instrument and at its inner end 80 to the shaft of the break wheel, pawl 12 riding over the ratchet teeth R in the usual way. After being set the device is prevented from running down immediately by any suitable lock on the clock train, in the 85 present embodiment comprising arm 13 adapted to engage with lug 13' on escape wheel 12^c. The arm 13 is carried by armature 13^a of magnet J and is withdrawn from lug 13' when said magnet attracts its armature to the position shown in Fig. 1. The clock train is so geared to the break wheel A that escape wheel 12^c makes one complete revolution for every new contact on break wheel A passing beneath brush N. The 95 push-buttons D upon disk A^x are formed as shown in Fig. 3, in which a stem D^a extends through a guiding socket P and a perforation in said disk A^x. The socket P has upper and lower stops 15^x and 15^y in stepped 100 relation upon its shell, as shown in Fig. 3, and the stem D^a of the push-button D carries a cross-pin O, one end of which is adapted to engage these stops 15^x and 15^y for holding the button D in lower and upper position, respectively. A coil spring 15 surrounding stem D^a tends to rotate said stem 105 so as to engage pin O under lower stop 15^x.

when the button D is depressed. When button D is in its lower position, one end of pin O is in a plane to engage armature pawl 8 fixed to armature 13^c, and the other end of pin O as shown in Fig. 1, is adapted to engage dog 9 pivoted to the frame and having a rear tail 22 pressed against a stop 22^a by spring 10.

This transmitter is of the usual latent type as described in my previous patents, and the circuit for controlling the same may be of the usual type therein described in which a closure is made at the distant station to energize the magnet J and thus allow the transmitter to operate and give its signal. For the purpose of disclosing the transmitter construction this circuit need not be shown further than the entering line 91 leading to the magnet, and thence by insulated connections 91^a to the brush N. The toothed contacts of the break wheel A of course are grounded to the frame of the machine, so that the current passing thereto from the brush N is led away by return wire 92.

A receiving instrument may be used with my transmitter such as that illustrated in Fig. 10. Such a receiving instrument may comprise an electro-magnet a which, when energized by an impulse, attracts the armature a' so that the pivoted pawl a² will rotate the ratchet a³ through one tooth space. After each impulse passes the armature a' drops down by gravity so that the pawl a² engages the next lowest tooth preparatory to giving the ratchet wheel the next rotation. The ratchet wheel is provided with a detent pawl a⁶.

The operation of the device shown in Fig. 1 is as follows: The apparatus is wound up for operation by turning the disk A^x and brake wheel A to the right to put tension on spring 3, which turning permits pawl 12 to ride over the ratchet in the usual manner, holding the spring 3 in its wound up position. The teeth of the ratchet R are arranged so as to stop the break wheel A with one of its contact teeth beneath brush N for keeping this part of the circuit closed. Since the circuit is normally broken at the distant station, magnet J is not energized and therefore arm 13 is in position to stop the clock train from running down. Assuming now that the operator wishes to set this transmitter for sending several different signals, he depresses several different buttons upon the disk A^x corresponding to the signals which he wishes to send. Assuming then that the operator at the distant station is ready to receive the signal from this transmitter shown in Fig. 1, he closes the circuit at that distant station in the way indicated in the patents above referred to, thereby energizing the magnet J, releasing the clock-work and allowing disk A^x and break wheel

A to turn anti-clockwise. During this rotation the break wheel A passing beneath brush N sends impulses to line, and this will continue until one of the depressed buttons D comes to the position shown by button D^x, at which time the pin O engages pawl 8 and stops the rotation of the disk A^x and break wheel A. It will be noted that the contacts on break wheel A correspond in number to the buttons D, and that when any button such as D^x engages pawl 8, a live contact of break wheel A lies beneath brush N so as to continue the circuit. This continuation of the circuit being transmitted to line instead of the usual interruption, may be translated by any suitable apparatus at the receiving end of the line into the proper signal showing which button was depressed. Moreover, the closure of this circuit caused by stopping the break wheel at this point continues until broken at some other place in the line, either manually by the operator at the receiving station, or automatically in some such way as shown in my Patent #573,592. When, however, the circuit is broken at some other place in the line, the magnet J releases pawl 8 and allows the disk A^x to continue its rotation. Upon this movement the pin O of the depressed button D^x is engaged by the dog 9 and swung circumferentially against the force of its spring 15 so as to be raised against its upper stop 15^a, Fig. 3, whereby the button is restored. The rotation of the disk A^x will thus continue until all of the depressed buttons D have given their signal and have been restored. In this manner the instrument may be set any one time for transmitting several different signals over the line in the same operation.

In the embodiment shown in Fig. 2 of the drawings, I have shown a modified form of transmitter in connection with a novel circuit arrangement. The instrument of this modification comprises as before, a break wheel A having contact teeth for sending impulses to line, said break wheel being fixed to its ratchet 2 and adapted to drive in one direction a disk 20 through a spring pressed pawl 12. The break wheel is turned by means of any suitable motor such as coil spring 3 as shown, and is provided with handle L for being turned to wind up said spring. The pawl 12 on disk 20 of course holds the break wheel in its wound up position and although this disk 20 is adapted to turn, nevertheless its rotation under driving force of ratchet 2 is regulated and controlled by a suitable clock work and escapement not herein shown but which may be of the usual form such as described in connection with Fig. 1 or in any of my previous patents above referred to. Surrounding the rotary disk 20 and spaced from its periphery is mounted a stationary ring 201

which ring carries a number of push buttons D^2 formed at their lower ends like a punch (not shown). A record strip of paper or the like 17 is guided over roller 16 around the periphery of rotating disk 20 and out by roller 18, said paper strip lying between disk 20 and its surrounding ring 201 and adapted to be fed in a continuous manner by said disk 20. Buttons D^2 are provided with the usual coil springs 15 and act to punch holes in the perforated strip 17, in a manner well understood, at regular intervals around the periphery of disk 20 so that a signal or signals will be transmitted as hereinafter described, and also provide a permanent record in the strip 17 of the signal which was transmitted. In addition to the button punches D^2 I have also provided in this instrument means for punching a second row of perforations in the strip 17 as shown in Fig. 4, which means may be either a second row of punches similar to D^2 or as shown, a swinging punching device comprising punch 55 carried on arm 56 which is pivoted to the shaft of the break wheel. It is understood that the circular ring 201 is formed with perforations (not shown) around its periphery, suitably indicated for signals, which allow punching device 55 to pass therethrough for punching a second row of perforations in strip 17. The magnet J, a portion of which is shown at the lower part of said figure, performs the same function as the magnet in Fig. 1, namely that of holding the clock train connected with the break wheel A from operating until said magnet is energized. The rotation of the break-wheel is preferably effected by means of a spring-motor comprising a spring 3' and including an escapement-wheel t^1 which is driven through speed up gearing including a gear-wheel t . The escapement-wheel t^1 cooperates with the verge t^2 and carries a stop t^4 near its edge. The gearing is proportioned so that the escapement-wheel t^1 makes one revolution to correspond with each metallic transmitting segment or strip of the break-wheel. The wire 92 which leads to the brush N has a branch connection passing through the coil of magnet J and passing from there the conductor 53^a leads to the contact fingers 53 and 54. When the current is not passing through the coil of magnet J, the spring t^5 holds the armature t^3 away from the magnet so that there is no obstruction in the path of the stop t^4 carried on the escapement-wheel t^1 . Mounted in any suitable manner upon the stationary frame and insulated therefrom are spring contact feelers 53 and 54 which as shown may extend through the ring 201 so as to bear against the tape or strip 17. These feelers 53 and 54 are adapted to detect the presence of perforations in the strip 17 and by means of circuit connections here-

inafter described, affect the circuit at a distant station. Detector 53 of course operates through one row of perforations and detector 54 through the other row of perforations in the strip 17. The circuit connections in this modification are also suitable for other forms of transmitters than the one here shown, and it is understood that one or more transmitters such as 61'' may be connected in line. The transmitters 61 are preferably similar to each other and are wired in multiple arrangement as indicated in Fig. 2 in which one of the instruments is shown on a small scale and the other on a large scale. Whenever the instrument is set by turning handle L and ratchet 2 and break wheel A clockwise, the pawl 12 will hold said ratchet 2 with a contact tooth beneath brush N in the usual manner for making a closed circuit. This circuit is closed through magnet J, line 92, spring jack 67, annunciator drop 67', bell 72, battery 90, line 91, branch 91'' to the frame 19 to which break wheel A is grounded. The current from battery 90 is not sufficient to energize the magnet J and consequently upon the closure of this circuit merely the annunciator drop 67'' and bell 72 are operated at the distant or central station to indicate to the operator at that place that a signal has been set in the transmitter ready for transmission. The operator at the distant station when it suits his convenience inserts plug 80 into the jack 67 which, in the usual manner, introduces into the line battery 89 which is of sufficient strength to operate magnet J. The spring jack 80 may be of any suitable construction such as described in some of my previous patents referred to, so that when introduced into the jack 67 it will close circuit to battery 89 and cut out the circuit through 90. The magnet J being thus energized through the second circuit from battery 89 releases the clock work in the usual way and break wheel A starts rotating to send impulses to line and in its rotation carries disk 20 and record tape 17. The record tape thus brings its perforations beneath feeling detectors 53 and 54 and the device is so arranged that whenever a perforation of this tape arrives beneath detector 53 for instance, an insulating block of break wheel A arrives beneath the brush N which would normally break the circuit. The detector 53 in this instance is a current carrying member so as to establish a short circuit around the break wheel by means of branch 53^a, detector 53, disk 20 and out by 91''' as before. In this manner the circuit instead of being broken in regular sequence is kept closed, but this continuous current does not advance the receiving instrument at the receiving station. The finger 53 cooperates with another finger or detector 54 which is con-

trolled by a second row of perforations in strip 17 to also establish a second time, a short circuit around break wheel A. The current normally passes by the conductor 92 to the brush N and when the break-wheel is in the proper position the current passes through the break-wheel and through the frame 19 of the instrument, then by conductors 91'' and 91''' to the line-wires 91' 10 and 91 which lead through the instruments 83' and 83 and back to the battery 89. The break-wheel operates as an impulse creating device and each impulse advances the pointers of the receiving instruments 83 and 83'. 15 When one of the perforations in the tape 17 comes under one of the fingers 53 or 54, the break-wheel is short-circuited and the current instead of passing to the brush N then passes through the coil magnet J and 20 through the finger 53 or 54 to the frame. From the frame the current passes as before through both receiving instruments, but this current is now a continuous current and not impulsive, so that it does not advance the 25 pointers of these instruments. Furthermore, the energizing of magnet J attracts its armature t^3 overcoming the force of spring t^5 and pulls the armature into the position indicated in Fig. 2 in dotted lines. This 30 brings the end of the armature into the path of the stop t^4 on the escapement wheel t^1 and stops the rotation of the break-wheel. The operator at the central station then 35 opens the circuit through either one of the instruments 83, 83', so that that signal maintains its pointer in the position where it is left. In this way the first signal remains indicated on one of the instruments. The 40 perforation in the tape is arranged so that when the finger comes in contact with the wheel 20, the brush N will be in contact with one of the insulating sections in the break-wheel. When the operator opens the circuit through wire 92, the armature t^3 is 45 released and the motor starts. The impulses which are produced in the line by the break-wheel now advance only one of the receiving instruments, namely that receiving instrument which has been left in closed 50 circuit. When the complete signal has been transmitted, the other of the fingers 53 or 54 may coöperate with the perforation in the tape 17 and short-circuit the break-wheel as before. A separate receiving instrument 55 such as 83' may be placed in this circuit so as to indicate any of the signals intended to be given by the second row of perforations. Since any suitable device may be arranged to close the shunt circuit through 60 91'' when the finger 54 drops into a perforation of the strip 17, the particular details of such a device are not herein shown. At each impulse the receiving instrument shown in Fig. 10 is advanced through one tooth space. 65 In order to prevent the currents in the

different transmitters 61'' from interfering with each other, the magnets for these different transmitters may be set in opposition.

It will thus be seen that by this arrangement the capacity of the transmitting instrument is greatly increased and may be extended in the same manner to almost any limits desired.

In the modification shown in Fig. 5, the buttons D are mounted in a stationary disk plate A^2 and these buttons are constructed in precisely the same manner as those of Fig. 1 in which a spring pressed stem 15 is adapted to be held in lower positions against stepped notches 15' by means of a cross pin O. When in their lower position pins O are in the plane of arm B so as to close a contact therewith for sending the signal of the depressed button in the manner hereinafter described. The magnet J in this instrument is arranged when energized to operate with a rheotomic effect, and therefore the usual break wheel and clock train is omitted. A ratchet wheel 4 is rotatably mounted adjacent said magnet and carries contact arm B. The coiled spring 3 normally tends to rotate the ratchet wheel 4 in a counter clockwise direction, and the pallets 23'' and 23' carried on pivot armature 23' coöperate with the teeth of ratchet wheel 4 to allow the same to turn in step-by-step rotation back to its original position shown in Fig. 5 in which arm B abuts against stop 46 and insulating block 51 rests beneath contact spring a^2 . The retracting spring 24' normally tends to lift armature 23' away from magnet J as soon as the circuit is broken in the manner presently to be described.

The operation of the transmitter shown in Fig. 5 is as follows: After the arm B is turned clockwise to wind up the spring 3 and also clear insulating block 51 from beneath brush A^2 so as to close a circuit through the face of the wheel 4, one or more of the buttons D are depressed to give their signals. If the line is then closed at the distant station in the usual manner by the receiving operator, (said operator presumably having been notified by any suitable annunciator drop and separate circuit not here shown) current enters at 91 passes through the magnet J, line 52, 52', contact 47, spring contact 48', line 23, and brush A^2 , face of wheel 4, grounded to frame and out at 92. As soon as the magnet J is energized and attracts its armature 23' allowing ratchet wheel 4 to rotate one step, the magnet is immediately deenergized by the breaking of the circuit at 47, 48', and the retracting spring 24' throws armature 23' outwardly again to hold ratchet wheel 4 until another movement. This rheotomic action continues as long as the current is on thus sending periodical breaks out to line in the usual manner. When, however, arm B strikes

against a depressed pin 0, a short circuit will be established around the contacts 47, 48^a which at this time in the regular operation of the device would be separated. The short circuit is established through line 52, 5 spring 4^a, insulated hub of arm B, through said arm to pin 0, grounded to frame and out at 92. When this happens the magnet J continues to be energized and thus holds its 10 armature down and pallet 23^a in locking position adjacent wheel 4 until the line 91 is broken from some outside source in the same manner as referred to in regard to Fig. 1. The continuation of the current 15 caused by this action, instead of the usual interruption, may be translated into a signal at the distant station.

Fig. 6 shows a still further modification of my transmitter which comprises an outer 20 stationary dial or cover plate JB with spring pressed buttons D extending therethrough. The stems 175 of the buttons D are guided as shown in Fig. 9 by cover JB and socket 44. Fixed to each stem is a collar 25 40 and a spring pressed detent 41 for a purpose hereinafter described. Mounted below the cover plate JB are two superposed disks 33 and 33^x fixed together by posts 49, 50 and cross-bar 39. These superposed 30 plates 33 and 33^x are arranged so as to be swung slightly on their centers, and the upper plate 33 is provided with recesses 33' adapted to register with the collars 40 and button stems 175 in one position so as to allow 35 said stems to pass therethrough and to be out of register with said collar 40 in its other position as shown in Fig. 9. The lower plate 33^x has slots 43 not in line with recesses 33' and which slots are adapted to 40 coöperate with the spring detent 41. In order to depress buttons D for setting a signal in this device, plates 33 and 33^x should be thrown counter clockwise of that shown in Fig. 6 to bring upper recesses 33' in register with collars 40. When the button D is 45 then depressed, its detent 41 springs beneath the lower disk 33^x and holds down the stem by reason of its being thrown to one side of the stem 175. The spring detent thus holds 50 the button down and when the plates 33 and 33^x are swung back to their original position, the upper plate 33, now out of register with collar 40, holds it in this depressed position, while the lower slot 43 now in register 55 releases spring detent 41. This position is here shown in section in Fig. 9. This arrangement particularly when used with a lock and key as hereinafter described, provides for locking the buttons either in their depressed or undepressed position so that 60 after the instrument has been set for a signal, it cannot be tampered with except by an authorized person. I have so far described the setting part of this modification 65 and will now proceed to describe the oper- ating parts thereof: Rotatably mounted on the frame is the ratchet wheel 5 having a retaining pawl 38 and adapted to be actuated step-by-step by hook pawl 37 carried on armature 37" of magnet J. Spring 37' acts 70 to throw back the armature after each attraction. The ratchet wheel 5 has fixed thereto arm B which carries at its outer end spring closed contacts 35. The current for energizing magnet J enters at 91, passes 75 through magnet J, branch 52, brush E, insulated hub of arm B, line H, contacts 35, arm B, grounded to the frame and out at 92. In its original position before being set for a signal, arm B stops at the position shown 80 in Fig. 6 with spring pressed contact 35 against insulating block 36 so as to break the circuit at this point. In setting this instrument the operator first oscillates disks 33 and 33^x by throwing arm 25 attached to 85 lower disk 33^x to the right to bring recesses 33' in register with the button collars 40. The buttons are then depressed for setting the several signals as desired. In this first movement of the plates 33 and 33^x, pin 45 90 carried on lower plate 33^x and arranged to bear against the tail of armature 37" throws the armature down to hook pawl 37 thereof on a fresh tooth of ratchet wheel 5. The return of plate 33^x to its original position for 95 locking the buttons in their depressed position allows armature 37" to retract fully under force of spring 37' to move ratchet 5 one step and thus close the circuit at contacts 35. The instrument is now ready for 100 transmitting its signal by closure of the line at the distant station in the usual way as described with reference to the other figures and in my previous patents referred to. In this device however, as shown in Fig. 6, 105 the oscillation of armature 37" is produced by impulses of current which arrive over the line from the distant station. These impulses may be given to the line by a receiving instrument such as is described in my 110 co-pending application Serial No. 93,286² filed on the same date herewith, in which a resistance is intermittently thrown into the line for weakening the same periodically. The magnet J of transmitter shown in Fig. 115 6 therefore is adapted to be energized only by the strengthening of the current caused by cutting out the resistance at the distant station. Thus the ratchet wheel is operated step-by-step by the intermittent movement 120 of the magnet armature. The current sent to line by this transmitter is however not broken up into impulses by a break wheel or analogous device as is the case with the other modifications herein described. When 125 arm B arrives opposite a depressed button D, collar 40 of said button is in a plane to engage the spring 35 and break the contact at this point, thus stopping the current altogether. The break in the line thus caused, 130

is translated into a signal by any suitable receiving device, for instance that shown in the co-pending application above referred to.

In order to prevent the present apparatus from being tampered with by unauthorized persons, I have provided a special key for unlocking the same. This key is shown more clearly in Figs. 6 and 8 and consists of a crescent-shaped end 31' adapted to engage the lower portion of arm 25 and when turned swing said arm to the right. A properly constructed key-hole may be made for receiving this form of key, and said key also may be provided with an extension 31^{ax} 15 adapted to coöperate with any suitable locking device so that only the properly fitted key may be used. In order to identify the operator at this transmitting station, the key is arranged to make a record upon a properly fed record tape such as 28. In the device shown, tape 28 is led from supply roll 27 around feed roller 29 and over roller 30. A hook pawl 26 carried on arm 25 engages ratchet teeth of said feed roller 29 to 20 hook the same forward one step upon every oscillation of arm 25, thus feeding forward a fresh surface to be printed upon. The end 26^a of the crescent-shaped key may be provided with a suitable impression device for 25 printing upon the tape 28 when said key is turned to the right.

What I claim is:—

1. An electrical signaling apparatus comprising a signal device having a plurality 35 of movable members for setting latent signals and operating means for receiving the signal indicated, and for restoring each movable member only after its respective signal has been taken.
2. In apparatus of the class described, in combination, a transmitting instrument, a plurality of receiving instruments, means for setting up different latent signals on said transmitting instrument, means for forming 40 circuits to transmit said latent signals to said receiving instruments respectively in succession, and means for automatically arresting the transmitting operation after the transmission of each latent signal.
3. In apparatus of the class described, in combination, a transmitting instrument, a plurality of receiving instruments, means for setting up different latent signals on said transmitting instrument, means for forming 45 circuits to transmit said latent signals to said receiving instruments respectively in succession, said transmitting instrument comprising an impulse creating device for breaking the current up into im-
- 60 pulses, and means for automatically short-circuiting said impulse-creating device after each signal has been transmitted.
4. In apparatus of the class described, in combination, a transmitting instrument, a plurality of receiving instruments, means

for setting up different latent signals on said transmitting instrument, means for forming circuits to transmit said latent signals to said receiving instruments respectively in succession, said transmitting instrument comprising an impulse creating device for breaking the current up into impulses, means for automatically short-circuiting said impulse-creating device after each signal has been transmitted, and electrical means for controlling the movement of said impulse-creating device. 75

5. In apparatus of the class described, in combination, a transmitting instrument, a plurality of receiving instruments, means for setting up different latent signals on said transmitting instrument, means for forming circuits to transmit said latent signals to said receiving instruments respectively in succession, said transmitting instrument comprising an impulse creating device for breaking the current up into impulses, means for automatically short-circuiting said impulse-creating device after each signal has been transmitted, mechanical 80 means for driving said impulse-creating device and electric means for controlling the operation of said last means. 85

6. In apparatus of the class described in combination, a transmitting instrument, a plurality of receiving instruments, contact fingers corresponding to said receiving instruments, circuits connecting said transmitting instrument to said receiving instruments to transmit latent signals to said receiving instruments, a member adapted to be advanced past said fingers and having means coöperating with said fingers to affect the circuits and control the signals being transmitted therethrough, said last 100 means including perforations to receive said fingers and form short-circuits, and means operated by the short-circuits for arresting the transmission of the signals. 105

7. In apparatus of the class described in combination, a transmitting instrument comprising a rotatable wheel, a plurality of receiving instruments, fingers mounted adjacent to said wheel, said transmitting instrument including means for transmitting 110 impulses to said receiving instruments, a tape adapted to be advanced by said wheel and having perforations coöperating with said fingers to short-circuit said impulse creating means to arrest the transmission of 115 the signal. 120

8. In apparatus of the class described in combination, a transmitting instrument comprising a rotatable wheel, a plurality of receiving instruments, fingers mounted adjacent to said wheel, said transmitting instrument including means for transmitting impulses to said receiving instruments, a tape adapted to be advanced by said wheel and having perforations coöperating with 125 130

said fingers to short-circuit said impulse creating means, and means for automatically arresting the transmission of the signal when the short-circuit is formed.

5 9. In an electrical signaling apparatus, a signaling mechanism, comprising a plurality of push-buttons for conditioning such mechanism to indicate separate signals subsequently to the separate operation of said buttons, separate means for subsequently receiving and indicating the signal intended by the said operation, and means for restoring normal conditions in said mechanism after the intended signals have been received

10 15 in succession by said separate receiving and indicating means.

10. In an electrical signaling apparatus, a signaling mechanism, comprising a plu-

rality of movable members for conditioning such mechanism to indicate separate signals 20 subsequently to the separate operation of said movable members, separate means for subsequently receiving and indicating the signal intended by the said operation, and means for restoring normal conditions in 25 said mechanism after the intended signals have been received in succession by said separate receiving and indicating means.

In witness whereof, I have signed this in the presence of two witnesses, on this 10th 30 day of February, 1902.

F. BENEDICT HERZOG.

Witnesses:

EDWARD Y. PURDY,
DANIEL J. MALONEY.
